ABSTRACT OF THE DISCLOSURE

Tetraorganolead compounds containing at least two different organosubstituents are reacted in the presence of a silicon tetrafluoride catalyst to produce mixed organolead compounds.

The instant invention is concerned with a method for producing mixed tetraorganolead compounds. More particularly, the invention relates to a method for producing a mixture of tetraalkyl lead compounds with the use of a certain catalyst.

Recently, efforts have been made toward devising a simple, economical method for producing a mixture of organolead compounds, which mixture would find ready use as an antiknock additive. If such a mixture could be made whereby the many lead components would have varying boiling points, the composition mix would then be better suited for use as an antiknock ingredient for hydrocarbon fuels. These fuels are generally a mixture of varying petroleum fractions having considerably different boiling point ranges, which fractions in their entirety encompass a rather broad boiling point range.

It would be desirable if a mixture of tetraorganolead compounds such as tetraalkyl leads could be made either from a combination of lead alkyls, each having four identical alkyl groups, but with alkyl groups differing between two or more tetraalkyl leads, or from a single or more tetraalkyl lead compounds each one of which has two or more different alkyl groups. Such a mixture itself would also have a broad boiling point range according to the number and type of lead components going to make up the mixture. These lead components in turn would volatilize with the various petroleum fractions, and thus impart excellent antiknock properties to the petroleum hydrocarbon mixture, even though such mixture contains a multitude of different hydrocarbon components which vary widely in their volatilization properties. Improved performance characteristics therefore would be imparted by such a mixture of tetraalkyl lead compounds to all types of hydrocarbon mixtures which may find use in autos, diesels, and the like.

A further advantage would be realized if the components of the tetraalkyl lead mix could be predetermined by some method whereupon the lead alkyl mix composition could be tailor-made for a variety of fuel performance requirements.

It would be an advance in the art if a mixture of alkyl lead compounds could be produced by a simple, single-step, inexpensive method. Other advantages would be gained if by such a method a lead mixture may be produced within a relatively short period of reaction time, without resort to elevated temperatures. Yet such process should have at least a minimum reaction period so that it can be conveniently terminated at any time to yield the desired proportion of mixed lead compounds.

U.S. Patent Nos. 3,151,141 and 3,151,142 describe methods for producing a mixture of tetraalkyl lead compounds. However, the processes described therein have certain drawbacks. For example, the disclosed use of

boron catalysts leads to a situation of a too rapid redistribution of alkyl lead reactants. This results in a lack of sufficient time to properly follow the reaction by analytical methods and quench the catalyst and reaction when the desired lead mixture is reached. That is, the rapidity of the reaction does not allow one sufficient time to analyze aliquots of the process mix and cease reaction when the indicated proportion is reached. Following the patented processes does not allow one of the desired time lag necessary to carry out an analysis program.

It would be a step forward if a method could be discovered for rearranging lead alkyl radicals to produce a tetraalkyl lead composite thereof, through use of a catalyst system which is versatile enough to allow one sufficient time to follow the reaction and thus quench at the desired point, but yet catalyzes the reaction rapidly enough to be commercially attractive. Further advantage would be realized if such a catalyst would have little or no susceptibility to product or reactant contamination, and could be used in a variety of solvent systems.

Again, it would be a distinct advance in the art if a method of producing a tetraalkyl lead composite were known in which both the reaction rate and the final products of the mix could be controlled by varying one or more process variants such as quantity of catalyst employed, time, and/or temperature. If a continuous method for producing a mixture of alkyl lead compounds were known, which process could be conveniently carried out at room temperature in a relatively short time, such a process would find ready acceptance, with the products thereof constituting an excellent source of motor fuel antiknocking agent.

It, therefore, becomes an object of the invention to provide a method for producing a mixture of tetraorganolead compounds by a single step, efficient process which may be carried out at room or elevated temperatures within a relatively short time.

Another object of the invention is to provide a method of producing a tetraalkyl lead mixture, in which mixture, lead compounds are present in proportions tending to approach a theoretical equilibrium mixture according to statistical laws of distribution which are stated in more detail below.

A specific object of the invention is to provide a mixture of tetraalkyl lead compounds which have for their radicals, methyl and ethyl groups, obtained by metathetical reactions which are catalyzed by a certain catalytic material, which reaction may be carried out in a relatively short time even at room temperature, and yet has sufficient flexibility so that the reaction may be stopped at any point short of theoretical equilibrium.

In accordance with the invention, has been found that a mixture of tetraorganolead compounds such as tetraalkyl lead compounds may be produced by rearranging a reaction mixture composed of one or more tetraorganolead compounds containing at least two different organosubstituents in the presence of silicon tetrafluoride catalyst in order to rearrange the organo constituents and produce a new mixture of lead compounds in proportions tending to approach a theoretical equilibrium mixture. While discussion below of the process will be presented in terms of tetraalkyl lead compounds for purpose of simplicity, it should be understood that the organolead substituents may widely vary without departing from the scope of the invention.

The equilibrium mixture, or proportions of various compounds of the mixture tending to approach this equilibrium, may be simply and easily synthesized through a variety of starting materials. For example, a simple mixture may be made of two or more tetraalkyl lead compounds each one of which compounds contain four

identical organic radicals, but with radicals differing in at least two occurrences between respective lead compounds. For example, a mixture of tetraethyl lead and tetramethyl lead may be made and then the radicals rearranged by means of catalyst at room temperature or at elevated temperatures. A metathetical reaction takes place wherein a variety of different compounds are produced having varying numbers of ethyl and methyl groups. These compounds are produced by rearrangement and/or exchange of radicals of tetraethyl lead and tetramethyl lead. It is to be understood, of course, that a number of lead compounds may be mixed and redistributed with catalyst, with the only requirement being that at least two different alkyl radicals are present in order for the rearrangement and/or exchange to take place. Also, the reaction may be terminated at any point prior to completion by quenching the catalyst with a material such as water or any other polar solvent. Thus, any desired combination of lead alkyl compounds may be simply made.

Another way of practicing the invention is to take a single tetraalkyl lead compound which has at least two different alkyl groups substituted thereon and contact this compound with the silicon tetrafluoride catalyst in order to produce the theoretical number of compounds having ratios in such proportions as may be predicted by statistical laws of distribution, according to a theoretical calculation of the mixture which would be obtained at complete equilibrium. Again, two or more heterogeneous tetraalkyl lead compounds may be employed, that is, compounds having at least two different alkyl lead radicals substituted around the lead atom. Likewise, one or more heterogeneous tetraalkyl lead compounds may be combined with one or more homogeneous tetraalkyl lead compounds, the latter being compounds having the four positions around the lead atom substituted with like radicals. These mixtures may also be rearranged by simple catalyst contact.

The radicals which may be rearranged on the lead

substituents. Again, such lead compounds containing groups as phenyl, and substituted phenyl may also be employed in the rearrangement process of the invention.

If, one reacts, for example, one or more compounds in which there are present both methyl and ethyl radicals, there will be obtained a metathetical reaction which will eventually reach an equilibrium, dependent only upon the ratio of the number of methyl groups to the number of ethyl groups initially present, irrespective of the type of compound or compounds chosen as starting materials. If it is presumed that the methyl ethyl lead compounds produced are thermodynamically equivalent, then a theoretical equilibrium distribution of methylethyl leads corresponding to any starting ratio may be given by the terms of the binomial expansion $(P+Q)^5$ where P is the mol fraction of methyl groups and $Q=(1-P)$ is the mol fraction of ethyl groups.

Table I below shows the theoretical mol ratios of various components of a tetraalkyl lead mix composition which may be produced by varying the mol fractions of the methyl and ethyl groups. The equilibrium mol ratio concentrations, of course, are theoretical, and may not be exactly reproduced by various experiments due to varying thermodynamic factors. However, mixtures having mol ratios extremely close to the theoretical equilibrium distribution may be produced. Also, the metathetical radical exchange reaction may be stopped at any point desired by the experimenter, short of the theoretical equilibrium distribution. Not only may the reaction be terminated short of equilibrium, to obtain varying ratios of different lead alkyl compounds, but also the products from the metathesis of starting mixtures of dissimilar compositions may be also blended together to produce different mix compositions. Table I below shows a number of typical theoretically attainable compositions that may be produced by equilibrating mixtures containing various mol ratios of tetraethyl lead to tetramethyl lead, and various mixtures which may be obtained by blending various quantities of equilibrates.

TABLE I.—TYPICAL THEORETICALLY ATTAINABLE COMPOSITIONS
[Mol percent]

Range	Et ₄ Pb	MeEt ₃ Pb	Me ₂ Et ₂ Pb	Me ₃ EtPb	Me ₄ Pb	Remarks
1-----	6	25	38	25	6	Equilibrate equimolar mixtures of tetraethyl lead (TEL) and tetramethyl lead (TML).
2-----	41	41	15	3	0	Equilibrate a mixture containing TEL, TML in a 4:1 mol ratio.
3-----	30	17	6	17	30	Equilibrate mixtures containing TEL and TML in 7.33:1 and 1:7.33 mol ratios. Blend equal quantities of the equilibrates.
4-----	20	20	20	20	20	Equilibrate mixtures containing TEL and TML in a 2.45:1 and 1:2.45 mol ratios. Blend equal quantities of the equilibrates with additional TEL and TML. (Also nearly attainable by stopping short of equilibrium with 1:1 ratios TML and TEL.
5-----	6	14	25	33	23	Equilibrate mixtures containing TEL and TML in 1:1 and 1:4 ratios. Blend equal quantities of the equilibrates.

atom may vary over a wide range of chemical constituents. To obtain high mobility of radical exchange between molecules it is preferred that materials having lower alkyl radicals be employed as reactants. Such materials may contain radicals as methyl, ethyl, isopropyl, n-propyl, tetrabutyl, isobutyl, n-butyl, etc. It is to be understood, of course, that higher alkyl radicals may also be rearranged through the method of the invention. However, in some of these cases involving the long chain radicals, in order to reach the desired mixture of compositions, it may be necessary to contact the starting reactants with the catalyst material for longer periods of time than are necessary with the lower alkyl lead compounds. For simplicity of discussion, preparative examples and general experimental techniques will be explained with regard to reaction between tetraethyl lead and tetramethyl lead. However, exactly analogous situations exist in cases of radical rearrangement with other organo

As mentioned above, the redistribution reaction effected by the catalyst may be extended over a wide range of times. For example, depending upon the type of mixture desired, or how close to theoretical equilibrium the mix composition is desired, the tetraalkyl lead reactants may be rearranged for as short a time as $\frac{1}{2}$ hour or as long as 12 hours. Excellent conversion of reactants to various mixtures has been effected at from 1 to 6 hours. The average reaction time of the process of the invention is roughly ten times slower than a similar reaction utilizing boron trifluoride catalyst or derivatives, therefore leading to advantages discussed above.

Again, depending upon the choice of the experimenter, the contact of the lead reactants may be carried out at room temperature or elevated temperatures. It has been determined that at elevated temperatures the rate of conversion is sometimes too rapid to allow one to cease the

reaction at the desired point. Thus, effecting reaction at room temperature is preferred.

The redistribution of the lead alkyl compounds with the catalyst material may be carried out in a number of ways. In one method, the silicon tetrafluoride gas is bubbled into a liquid batch of lead alkyl reactant to initiate reaction. The reaction may be run in presence of liquid scavengers as ethylene dibromide or ethylene dichloride or a variety of solvents as ethers without adversely affecting the catalyst. Thus, the lead redistribution may be effected by first dissolving the lead reactants in any solvent which does not destroy the catalyst effectiveness and allowing the reaction to proceed to the extent desired.

The amount of catalyst used may be varied over a considerable range. Again, the rate of reaction is dependent to a degree upon the amount of catalyst employed. Excellent results have been realized through use of as little as 0.001% by weight of catalyst, based on the weight of lead reactant. Preferably, from 0.01 to 20% by weight of catalyst is employed, with optimum results effected through use of from 0.01 to 5% by weight of catalyst.

The reaction may be run in a variety of solvents or may also be carried out without benefit of solvation. Any organic solvent in which the lead compounds are compatible may be used. Among these are benzene, ethers as tetrahydrofuran, toluene, xylene, ethylene dichloride, carbon tetrachloride and the like.

It has been discovered that the presence of water either in the catalyst or as an impurity in the reactants severely retards the reaction and should be avoided. However, water has been found to be an excellent quench medium to terminate redistribution.

Experimental runs indicated that there is substantially no change in total alkyl lead concentrate, during the equilibration reaction. This indicates that there are no substantial side reactions taking place, and the metathetical reaction, which most probably takes place through some sort of free radical exchange, is a "clean" reaction, causing no difficult undesirable side effects.

Starting lead compounds may be made available by a number of known procedures. For example, the manufacture of organometallic compounds and, more specifically, organic lead compounds by electrolyzing a solution of a Grignard reagent in an organic solvent for the Grignard reagent is disclosed in U.S. Patents 3,007,857 and 3,007,858. In the process disclosed in the latter patent, an extraneous organic halide is added to the electrolyte.

A mixture of lead compounds can be made via the just-cited patented methods by separately electrolyzing different Grignard reagents and equilibrating the products after mixture thereof. Again, a mixture of alkyl lead compounds, such as triethylmethyl lead, diethyldimethyl lead, ethyltrimethyl lead, tetraethyl lead and tetramethyl lead may be produced by using as an electrolyte an ether solution of mixtures of methyl magnesium halide such as the chloride and ethyl magnesium halide. After electrolysis, the mixture may then be equilibrated according to the process of the invention by contact with catalyst with or without prior addition of lead compounds which may contain radicals other than the methyl or ethyl type. A variety of other Grignard reagents may also be electrolyzed singly or in admixture with one another. Specific examples of these Grignard reagents are ethyl magnesium bromide, isopropyl magnesium bromide, isopropyl magnesium chloride, butyl magnesium chloride, butyl magnesium bromide, amyl magnesium bromide, amyl magnesium chloride and higher alkyl homologues. Similarly, phenyl magnesium chloride, phenyl magnesium bromide or mixtures of phenyl and ethyl magnesium chloride, or mixtures of phenyl and ethyl magnesium bromide, or mixtures of phenyl and methyl magnesium chloride, or mixtures of phenyl and methyl magnesium bromide can be electrolyzed to produce a mixture of other organic com-

pounds containing the phenyl radical, or both the phenyl and ethyl radicals or both the phenyl and methyl radicals, or both the phenyl and other alkyl radical in case another halide is substituted for the ethyl magnesium halide or the methyl magnesium halide. Similarly, benzyl magnesium chloride in an organic ether can be employed alone or in mixture with one or more of the above-mentioned Grignard reagents or others to produce a suitable electrolyte. Thus, if a mixture of the Grignard reagents is employed, the resultant mixed lead compounds may be equilibrated without addition of a further differing lead compound. If, on the other hand, a single Grignard reagent is employed, at least one other differing organic lead compound must be added prior to equilibration in order to achieve an equilibrated mix or one tending to approach a theoretical equilibrium mixture.

The term "Grignard reagent" as used herein refers to the product obtained by reacting approximately equimolar proportions of compounds having the formulae RX and Mg according to the equation:

in which R represents the organic radical, X represents the halogen atom of the Grignard reagent and Mg is the chemical symbol for magnesium. As outlined above, the radical R can be chosen from a wide variety of organic radicals, and as well, the radical X can be any halide, for example, chloride, bromide or iodide.

The following example is given to more fully illustrate the invention.

EXAMPLE I

A solution of 28.3% tetramethyl lead and 27.1% tetraethyl lead in a mixture of solvents of ethylene dibromide, ethylene dichloride and toluene was prepared. Silicon tetrafluoride catalyst was then bubbled into the solution. At the completion of the run, a gas chromatography analysis indicated extensive equilibration had taken place. Analysis of the equilibrated mix yielded the following percentages of various lead compounds present: tetramethyl lead, 8.7%; trimethylethyl lead, 12.3%; dimethyldiethyl lead, 17.7%; triethylmethyl lead, 14.0%; and tetraethyl lead, 3.2%.

It has been demonstrated that any type of tetraalkyl lead mix composition may be obtained as desired by adjustment of any one of the several process variables or by ceasing the metathetical reaction prior to its theoretical equilibrium completion. The products of the invention find valuable use as antiknock motor fuel additives and, may be used for a variety of other uses involving organo metallics, or as synthetic organic intermediates.

The invention is hereby claimed as follows:

1. A method of providing a mixture of tetraorganolead compounds, which comprises the steps of forming a reaction medium composed of at least one tetraorganolead compound, said medium including at least two different organoradicals, contacting said reaction medium with a silicon tetrafluoride catalyst in order to rearrange said organoradicals and produce a new mixture of organolead compounds in proportions tending to approach a theoretical equilibrium mixture.

2. The method of claim 1 wherein said reaction medium includes a tetraalkyl lead compound.

3. A method of providing a mixture of lead alkyl compounds with at least one component containing mixed alkyl radicals, which comprises the steps of contacting at least one lead tetraalkyl compound having at least two different alkyl radicals thereon with a silicon tetrafluoride catalyst in order to rearrange said alkyl radicals to produce said new and useful mixture of lead alkyl compounds.

4. A method of providing a mixture of lead tetraalkyl compounds with at least one component containing mixed

alkyl radicals, which comprises the steps of contacting at least two lead tetraalkyl compounds, each compound containing four identical organic radicals, but with organic radicals differing between at least two compounds, with a silicon tetrafluoride catalyst in order to rearrange said alkyl radicals to produce said new and useful mixture of lead alkyl compounds.

5. The method of claim 3 wherein said radicals are selected from the group consisting of methyl and ethyl.

6. The method of claim 4 wherein said radicals are selected from the group consisting of methyl and ethyl.

7. The method of claim 1 wherein said rearrangement reaction is terminated prior to reaching equilibrium by quenching catalyst activity by contact thereof with water.
